UNITED STATES PATENT OFFICE.

FRANZ EMIL WOLF, OF NOWAWES, NEAR POTSDAM, GERMANY.

EXHAUST-SILENCER FOR INTERNAL-COMBUSTION ENGINES.

1,032,794.

Specification of Letters Patent. Patented July 16, 1912.

Application filed May 13, 1910. Serial No. 561,053.

To all whom it may concern:

Be it known that I, FRANZ EMIL WOLF, engineer, a subject of the King of Prussia, and a resident of Nowawes, near Potsdam, 5 Germany, have invented certain new and useful Improvements in Exhaust-Silencers for Internal-Combustion Engines; and I do hereby declare the following to be a full, clear, and exact description of the invention, such as will enable others skilled in the art to which it appertains to make and use the same.

My invention relates to improvements in exhaust silencers for internal combustion 15 engines and its object is to provide a silencer which acts without obstructing the exhaust and reducing the efficiency of the engines, as is the case with silencers wherein the passage is narrowed and the direction 20 of flow of the gases reversed.

With this object in view my invention consists in conducting the exhaust gases through a passage or passages formed by a series of spaced disks, arranged axially 25 behind each other, and allowing the gases to radially traverse the space or spaces between said disks so that they can expand and are simultaneously subjected to friction and cooling on the surfaces of the disks.

Such friction of the gases on the disks may 30 be produced in various ways. For example the disks may be located in such proximity to each other that sufficient friction is produced, or the gases may be forced to travel 35 on curved paths, so that they are thrown against the walls when being deflected. Obviously both means may be combined in a single apparatus.

For the purpose of explaining the invention 40 several examples embodying the same have been shown in the accompanying drawing in which the same letters of reference have been used in all the views to indicate corresponding parts.

In said drawing Figure 1, is a vertical 45 section of an exhaust pipe and the silencer connected therewith, Fig. 2, is a cross-section of the silencer taken on the line 2—2 of Fig. 1, Figs. 3 to 5, are vertical sections 50 similar to that shown in Fig. 1 and illustrating modifications of the silencer, and Fig. 6, is a section of a part of a silencer which is similar in construction to that shown in Fig. 5.

Referring to the example illustrated in 55 Figs. 1 and 2, my improved silencer con-

sists of a plurality of disks *a* placed coaxially in series, and provided, with the exception of the outermost one *a*¹, with central openings *b*, the diameters of which are 60 equal to that of the exhaust pipe *c*. The first disk is jointed to the exhaust pipe *c* by means of a union *d*; the last disk *a*¹ forms a closure in the direction of flow of the gases. The disks are spaced apart by 65 spacing sleeves *f*, but connected by means of bolts *e*, so that they inclose annular flat intermediate spaces, through which the gases flow radially outward as indicated by the arrows. During this outward flow 70 the gases are enabled to expand, and are at the same time cooled by contact with the disks, so that they pass out at the periphery of the device comparatively silent.

The device is differentiated from previously known silencers by the fact that there is no reduction of cross section of the passage for the exhaust gases, but a progressive increase of cross section, whereby back-pressure on the power cylinders of the engine is obviated. The silencer is comparatively very small, and consequently of light weight, and cheap. The subdivision of the gases prevents silencer-explosions in case of failure of ignition. The distance of the 85 disks *a* from each other is sufficiently small to produce the friction required for slowing down the speed of the gases, and the diameter of the disks is such that the gases escape from the silencer almost noiseless. 90

To prevent dispersion of the exhaust gases at the periphery of the device, the disks *a* may be curved inward at their edges *a*², as shown in Fig. 3, so that the gases are deflected toward the center again. The exhaust gases may then pass into another discharge conduit. The re-narrowing of the passage in this form of the device has no disadvantageous effects on the working, inasmuch as the gases are cooled, before they 100 pass out of the spaces between the disks, and are consequently of smaller volume.

The construction shown in Fig. 3 also embodies a second means for producing friction of the gases on the surfaces of the 105 disks *a*, the gases being brought in close contact with the disks when being deflected on the curved portion *a*² of the same.

In Fig. 4 the gas-passages are undulated, by reason of corrugation of the disks *a*⁴, *a*⁵. 110 Such corrugation strengthens the disks and increases the contact-surface for the gases,

and friction of the same on the disks. Sinuosity of the gas-passages can also be obtained by providing the disks with ribs concentrically or otherwise disposed. Examples of this construction are shown in Figs. 5 and 6, with ribs of wedge-shaped cross-section. In Fig. 5 the disks a^6 and a^7 are joined together by means of bolts e^1 enabling them to be adjusted relatively to each other, to increase or reduce the gas-passages according to the power of the motor and the rate of exhaust. The same means enables the device to be easily cleaned, for which purpose the disks may be wholly disconnected.

In the example shown in Fig. 5, the grooves formed between successive ribs g and h are rounded at their bottoms, while in the modification shown in Fig. 6 the said grooves are formed with angular side faces.

I claim:

1. A muffler consisting of a plurality of plates fastened together in spaced relation, one of the outer plates of said muffler being formed with an inlet opening for the admission of the gases and the other of its outer plates being closed to compel the gases to flow outwardly over and between opposed faces of the plates; each intermediate plate being annular and having an opening the size of which is substantially the same as that of said inlet opening; the interval which separates the faces between which flow the gases being at the outer edge portions of the plates at least as great as the

interval between the same faces at the central portions of the plates, whereby throttling of the gases at their discharge from the muffler is avoided and friction is produced between the gases and the faces between which the gases flow; said faces being formed with a series of alternate ribs and grooves for the purpose herein set forth.

2. A muffler consisting of a plurality of plates fastened together in spaced relation; one of the outer plates of said muffler being formed with an inlet opening for the admission of the gases and the other of its outer plates being closed to compel the gases to flow outwardly over and between opposed faces of the plates; each intermediate plate being annular and having an opening the size of which is substantially the same as that of said inlet opening; the interval which separates the faces between which flow the gases being at the outer edge portions of the plates at least as great as the interval between the same faces at the central portions of the plates, whereby throttling of the gases at their discharge from the muffler is avoided and friction is produced between the gases and the faces between which the gases flow.

In testimony whereof I affix my signature, in presence of two witnesses.

FRANZ EMIL WOLF.
